(57) **CLAIM**

The ornamental design for a table/desk, as shown and described.

DESCRIPTION

FIG. 1 is a front perspective view of our new design, showing the table/desk at a first height;

FIG. 2 is a partial perspective view thereof;

FIG. 3 is a rear perspective view thereof;

FIG. 4 is a front view thereof;

FIG. 5 is a rear view thereof;

FIG. 6 is a left side view, the right side view being a mirror image thereof;

FIG. 7 is a top view thereof;

FIG. 8 is a partial, enlarged top view thereof;

FIG. 9 is a front perspective view thereof, showing the top at a second height;

FIG. 10 is another front perspective view thereof;

FIG. 11 is a front perspective view thereof, showing the top extended forward;

FIG. 12 is a front perspective view thereof, showing the top in a vertical position;

FIG. 13 is a front perspective view of a second embodiment thereof, showing the top of the first embodiment at a second height;

FIG. 14 is a front view of thereof;

FIG. 15 is a rear view of thereof;

FIG. 16 is a left side view, the right side view being a mirror image thereof;

FIG. 17 is a top view of thereof;

FIG. 18 is a partial, enlarged top view thereof;

FIG. 19 is a front perspective view of a third embodiment thereof, showing the top of the first embodiment at a third height;

FIG. 20 is a front view thereof;

FIG. 21 is a rear view thereof;

FIG. 22 is a left side view, the right side view being a mirror image thereof;

FIG. 23 is a top view thereof; and,

FIG. 24 is a partial, enlarged top view thereof.

The broken lines represent environmental structure that forms no part of the claimed design. The jagged lines represent boundaries of a partial view.

The drawings include CAD lines that represent contour and not surface decoration.

1 Claim, 21 Drawing Sheets
